UNITED STATES PATENT OFFICE.

EDOUARD SCHENK, OF GENEVA, SWITZERLAND.

SAFETY-PIN.

1,397,236.

Specification of Letters Patent. Patented Nov. 15, 1921.

Application filed September 20, 1920. Serial No. 411,423.

To all whom it may concern:

Be it known that I, EDOUARD SCHENK, citizen of Switzerland, residing at Geneva, Canton of Geneva, in the Confederation of Switzerland, have invented certain new and useful Improvements in Safety-Pins, of which the following is a specification.

This invention relates to safety catches for pins; and its object, stated briefly, is the provision of an improved catch which is applicable to breast pins, brooches, scarf pins and analogous articles of jewelry and which operates in a manner to effect the automatic locking of the pin consequent upon the mere act of closing it. The improvements comprised in the invention involve, primarily, a socket member or catch proper which is movable automatically into position to engage the point of the pin when the latter is closed, and a means or device whereby such member is held against displacement from its position of engagement until a positive releasing operation has been manually effected.

The accompanying drawing illustrates various ways in which the invention may be carried out.

Figure 1 being a side elevation of one embodiment, showing the pin in open position; Fig. 2 a fragmental detail view, partly in section, showing the pin closed;

Figs. 3 and 4 are transverse sections on lines 3-3 and 4-4, Figs. 1 and 2, respectively;

Fig. 5 is a longitudinal sectional view of a modification; and

Fig. 6 is a part-sectional side elevation of a third form of the invention.

In the first form, represented in Figs. 1 to 4, *a* indicates the body portion of the piece of jewelry (there shown as a brooch) to which the invention is applied, and *b* the pin member thereof, the pin being pivoted at one end at *c* in an enlargement or bearing *d*.

The free end or point of the pin is designed for engagement by a catch, consisting in this instance of a socket *e* which is mounted to slide between guides *g* provided on the back of the part *a* and is held in place by flanges

h on the guides that fit in lateral grooves in the socket. The latter is formed with a recess or bore to receive the pin point and with a second recess or opening in which is arranged one end of an expansible coil spring *i*, the other end of which bears against the rear end wall of the slot or guideway

produced by the said guides *g*; the spring thus tending to move the socket bodily in a direction toward the point end of the pin which, during its movements, travels in an 60 arc indicated at *x*.

The socket is adapted to be retracted manually, against the action of the spring, to bring it into a position beyond arc *x*, for which purpose it is formed with a finger-piece or flange *f* to permit it to be readily grasped; and means are provided which act to hold said slide in that position when the pin is open, but which automatically release it consequent upon the closing movement of 70 the pin. In the construction illustrated in Figs. 1 to 4, such means comprise a pawl *k*, which has one end forced into a groove or seat *n* formed in the body *a*, and the other end formed with a fork *l* that underlies the 75 pin; the intermediate portion of the pawl being provided with an upstanding tooth *m* for engagement with the front edge of the socket. This pawl is constructed in the form of a flat spring, and is so mounted and ar- 80 ranged that in the normal position of the parts, with the socket retracted and engaged by tooth *m*, the fork *l* will be elevated (see Fig. 1). Hence, when the pin is being closed, its point will press against the fork and 85 force it downward or inward toward the back of body *a*, thereby releasing tooth *m* from the socket and, incidentally, centering the pin point with respect to the bore or recess of the socket. When such release 90 takes place, the socket will be automatically forced toward the pin point by the action of spring *i*, which has previously been held in a tensioned condition, and will thus engage said point and lock the pin in closed 95 position.

To thereafter open the pin, it is necessary to first pull back the socket or catch by means of its finger-piece *f* until the pin point is completely withdrawn therefrom, whereupon the pin may be moved away from the body *a*, as will be understood. The backward movement of the socket has the double effect of contracting the coil spring *i* and uncovering the tooth *m* on pawl *k*, which latter, 105 by reason of its spring construction, will thereupon reengage the socket and hold the same in retracted or cocked position.

Fig. 5 represents a somewhat modified construction according to which the detent action—that is, the action exerted by the pawl in the first form—is exercised by an element

which forms an integral part of the pin itself. In this form, the body a^2 consists of a hollow tube which is closed at one end by an integral wall and at the other by a plug 5 r^2 which is mounted on a removable cross-pin or pivot s^2 . The sliding socket e^2 is cut away at its inner end, as indicated at l^2 , to form a guide opening for the point of the pin b^2 , and is attached to the adjacent end of 10 a second tube q^2 which is slidably fitted within the outer tube or body a^2 ; the neck e^{20} which connects the parts e^2 and q^2 projecting through and sliding in a longitudinal guide slot n^2 in said body a^2 . The end of the inner 15 tube q^2 to which socket e^2 is connected is left open in order to permit the insertion of the operating spring i^2 into the bore of the tube, said spring bearing at its outer end against the plug r^2 and at its inner end against the 20 end wall of the bore, so that the tendency of the spring is to force said tube in an inward direction. The inner end of tube q^2 is made solid, as indicated at q^{20} , and has 25 formed therein a cup-shaped seat or depression t^2 for coaction with an enlargement k^2 on the inner end of the pin b^2 , which enlargement fits in the bearing d^2 and is connected thereto by the pivot c^2 . The said enlargement projects into a slot a^{20} formed in line 30 therewith in the outer tube or body a^2 , and is of substantially circular shape, its radius being the same as that of the depression or seat t^2 , so that in one position of the sliding tube q^2 , its seat will register with slot a^{20} and 35 the disk or enlargement can be turned into position to extend into and occupy said seat, as hereinafter explained. The disk is also formed with a straight edge or cam k^{20} which is disposed parallel with the axis of 40 the pin and which is likewise designed for coaction with tube q^2 . In this form of the invention, the backward movement of the socket and, hence, of the tube e^2 is effected by means of a finger-piece f^2 which, instead of 45 being applied to the socket, is fastened to the tube q^2 by means of a screw shank which extends through a longitudinal slot u^2 in the body a^2 and is threaded into a hole in the solid end q^{20} of tube q^2 , the length of such 50 slot determining the extent of movement of tube q^2 in opposite directions. To preserve the symmetry of the brooch, or increase its artistic or intrinsic value, the finger-piece may take the form of a gem set in a suitable 55 socket, and there may be two of such finger-pieces, one at each end of the brooch.

Assuming that the parts are in the position shown in Fig. 5, it will be observed that the pin is held in closed position by a 60 double lock: its point is engaged in the socket e^2 , and the straight portion or cam edge k^{20} of disk k^2 is engaged with the sliding tube q^2 which will effectually prevent the pin from being moved outward. To open 65 the pin, it is necessary to shift tube q^2 to-

ward the plug end of the tubular body a^2 by means of its finger-piece f^2 , such movement withdrawing socket e^2 from the pin point and at the same time bringing seat t^2 opposite disk k^2 . The pin may then be swung 70 into open position, because the disk will be free to move into said seat; but it is to be observed that the projecting portion of the disk then disposed within the seat will prevent tube q^2 from being forced backward 75 by spring i^2 . Hence the said disk, in both of its positions, will exert a locking or detent action, analogous to that exerted by the pawls k and k' , in one of which positions it prevents the pin from being opened, and in 80 the other of which it prevents the spring i^2 from shifting tube q^2 and, hence, keeps said spring in tensioned condition. Thereafter, when the pin is moved inward by hand, the circular portion of the disk will be gradually moved out of seat t^2 and its straight portion k^{20} gradually brought opposite said seat; and when that position is reached, which occurs when the pin and socket are in 85 axial alinement, tube q^2 will be released and the socket will be engaged automatically with the pin end by the expansion of the 90 spring.

By extending slot n^2 through the end of tube a^2 , and making pin s^2 and finger-piece f^2 removable, it is possible to remove plug r^2 and then completely withdraw tube q^2 when 95 it is desired to have access to the interior of tube a^2 for any reason.

In the form represented in Fig. 6, the body 100 a^3 is tubular, as in the form shown in Fig. 5, and receives the sliding inner tube q^3 which carries the socket e^3 to engage the point of pin b^3 . The latter is provided with an enlarged disk-like part k^3 which is generally 105 similar to the disk k^2 and, like it, is designed to exert a detent action, as subsequently explained; said disk k^3 being centrally pivoted at c^3 in a bearing d^3 and projecting through a slot a^{30} into position to coact with tube q^3 . 110 The latter is generally similar to tube q^2 and is subjected to the action of a spring i^3 which, like the spring i^2 , is arranged within the tube.

The disk k^3 is provided with three teeth 115 v^3 for coaction with the teeth w^3 formed on the tube q^3 , the latter being cut away immediately in rear of its teeth w^3 for a distance equal to three tooth spaces; this cut-away portion being utilized to enable a certain amount of play between the disk k^3 and the said tube q^3 , during which movement the disk remains stationary. In addition to the set or series of teeth v^3 , the disk k^3 is provided with a pair of diametrically-opposite stops y^3 , located at the ends of such series and the purpose of which is to limit to a movement of 90° the swinging movement or stroke of the pin in either direction. The tube q^3 projects beyond one end of the 120 125 130

body a^3 , as shown, and carries a suitably-set terminal gem f^3 which functions as a finger-piece.

The parts may be assumed to be shown in

- 5 Fig. 9 in the positions which they occupy just at the moment when the cut-away portion of tube g^3 is immediately in line with the last tooth v^3 on disk k^3 , so that the ensuing movement of the tube caused by the
 10 expansion spring i^3 will not affect disk k^3 nor pin b^3 but will merely cause socket e^3 to become engaged with the pin point; it being understood that the initial portion of the movement of the tube by said spring i^3
 15 (during which time the rack-and-pinion action of the teeth w^3 on the teeth v^3 has caused the pin to swing inwardly into closed position) has already been completed.

When it is desired to open the pin, pressure is applied to the part f^3 to push tube g^3 inward. During the first part of such movement, said tube moves idly with relation to disk k^3 because of the presence of the cut-away portion, and its only effect is to move
 25 socket e^3 away from the pin point to release the same. As soon as the teeth w^3 and v^3 become engaged, however, disk k^3 will be rotated and will swing the pin outwardly into open position. When the pressure upon
 30 the part f^3 is removed, the controlling spring i^3 , which was previously compressed, forces tube g^3 outward; but since the lost motion provided for by the cut-away portion of said tube does not occur until the last part of the
 35 out-stroke of the tube, the rack teeth w^3 on the latter will immediately rotate the pinion or disk k^3 with the result that the pin is swung inward into line with the socket k^3 which will be engaged therewith during the
 40 last part of the movement of the tube, as above explained. Hence, in this form of the invention the closing or inward movement of the pin is effected automatically, whereas in the other forms such movement must be
 45 effected manually. In all of the forms shown and described the actual locking of the pin by the socket is automatic, and the pin remains locked until its release is effected by a positive manual operation serving to disengage the pin end from the
 50 socket.

I claim as my invention:—

1. The combination with a pin and a body to which it is hingedly connected, of a catch, and means for holding the catch out of pin-engaging position when the pin is open, said

catch being released from said means and moved automatically into engagement with the pin upon movement of the latter to closed position.

2. The combination with a pin and a body to which it is hingedly connected, of a spring actuated socket mounted for sliding movement on said body, and means for holding the socket out of pin-engaging position when the pin is open, said socket being released from said means and automatically moved by its spring into engagement with the point of the pin upon movement of said pin to closed position.

3. The combination with a pin and a body to which it is hingedly connected, of a catch, detent means for holding the catch out of pin-engaging position when the pin is open, and means for automatically moving the catch into pin-engaging position when said catch is released from said detent means, said catch being released from said detent means directly and solely upon movement of said pin to closed position.

4. The combination with a pin and a body to which it is hingedly connected at one end, of a catch, detent means carried by the pin and engaging the catch for holding the latter out of pin-engaging position when the pin is open, and means for automatically moving the catch into pin-engaging position when said catch is released from said detent means, said catch being released from said detent means only when said pin is in closed position.

5. The combination with a pin and a body to which it is hingedly connected at one end, of a socket mounted for sliding movement on said body and provided with a shank portion having rack teeth, a portion integral with the hinged end of said pin having detent teeth for engaging the teeth of said shank portion for maintaining said socket out of pin-engaging position when the pin is open, and a spring for moving said socket into pin-engaging position when released from said detent teeth, said socket being released from said detent teeth only when the pin is in closed position.

In testimony whereof I affix my signature in presence of two witnesses.

EDOUARD SCHENK.
